RECLOSING CIRCUIT BREAKER

James M. Wallace, East McKeesport, Pa., assignor to Westinghouse Electric Corporation, East Pittsburgh, Pa., a corporation of Pennsylvania

Application September 27, 1947, Serial No. 776,563

5 Claims. (Cl. 200—89)

1

This invention relates to electric circuit breakers generally, and more particularly, to operating mechanism means governing circuit opening time characteristics of a breaker.

In providing protection for a circuit against overloads and short circuits, various type of circuit interrupting devices are commonly employed at different points along the circuit, and it is highly desirable that these devices be coordinated as to operation for the ultimate purpose of isolating the faulty section or branch of the circuit without substantially disturbing continuity of service to the remainder of the circuit. Fuses are commonly used for the protection of certain apparatus and for the protection of branch circuits in which such apparatus is located, and automatic reclosing circuit breakers are used ahead of such fuses in the circuit for the purpose of ultimately isolating the faulty part of the circuit by requiring operation of the fuse protecting that part of the circuit. Each circuit breaker may thus be used to protect a number of fuses which may vary in current rating, with the breaker designed to open and reclose the circuit a number of times.

In order to properly coordinate with fuses which have an inherent thermal inverse time-current characteristic, various time delay means such as dashpots, mechanical tickers, etc., have been employed to give circuit breakers a circuit opening characteristic similar to fuses. Such devices enable a breaker to coordinate very well with fuses on low currents, but on high currents the resistance of such time delay means approaches infinity at least for a short time, and consequently coordination with fuses becomes extremely difficult.

One object of this invention is to provide a circuit breaker of the type described with novel time delay means to cause the breaker to have a circuit opening time characteristic closely approximating that of a fuse.

Another object of this invention is to provide a circuit breaker of the type described having novel time delay means for delaying a circuit interrupting operation and wherein the resistance offered by the time delay means decreases for high current interrupting operations.

Still another object of this invention is to provide a circuit breaker of the type described having a dashpot for delaying a circuit opening means, with novel means for decreasing the effect of the dashpot on high current circuit interrupting operations.

Another object of this invention is to provide

2

a circuit breaker of the type described having an overload responsive member which is normally movable a predetermined distance before causing a circuit interruption with time delay means delaying movement of said member, and with novel means responsive to high overloads for causing a circuit opening operation in response to a lesser movement of said overload responsive member.

Another object of this invention is to provide novel hydraulic and mechanical operating means for a circuit breaker which is selective in operation dependent upon the magnitude of overload to be interrupted.

These and other objects of this invention will be more apparent upon consideration of the following description of preferred embodiments of the invention, when taken in connection with the attached drawing, in which:

Figure 1 is a schematic view of a reclosing circuit breaker constructed in accordance with this invention, with parts of the breaker shown in section;

Fig. 2 is an enlarged partial sectional view through the breaker shown in Fig. 1;

Fig. 3 is also a partial sectional view similar to Fig. 2, but illustrating another embodiment of this invention;

Fig. 4 is also a partial sectional view of a circuit breaker similar to Figs. 2 and 3 but illustrating still another modified form of the invention, and

Fig. 5 is a chart illustrating time-current curves of fuses and circuit breakers.

The automatic reclosing circuit breaker diagrammatically illustrated in Fig. 1 of the drawing has a stationary contact 2 and a movable contact 4 mounted on the lower end of a movable contact rod 36. The upper end of contact rod 36 is pivoted as at 7 to a lever 8 which is pivoted as at 12 on a bracket 13 secured to the cover 14 of a casing 15 for the breaker. Lever 8 is biased in a clockwise direction by a coil tension spring 16 connected between a pin 20 on lever 8, and a pin 18 on bracket 13.

In order to separate movable contact 4 from stationary contact 2, a solenoid coil 22 which is annular in form is provided about contact rod 36 and is supported between spaced supporting plates 24 which may be stationarily mounted in casing 15 in any desired manner. Insulation 26, which may be of fiber or of a molded insulating material, is provided for lining the interior of solenoid coil 22, and preferably extending over the ends of the coil between the coil and stationary supporting plates 24. A hollow cup-shaped core 28 is adapted to

be slidably mounted on contact rod 36 and to slidably fit within the cylindrical passage 10 formed by insulation 26 of the solenoid coil in a piston-like manner. The lower limit of movement of solenoid core 28 on contact rod 36 is defined by a stop pin 31 provided on the contact rod. Solenoid coil 22 is connected in series with the breaker contacts 2 and 4 by a connection 33 between one end of the coil 22 and contact rod 36, with one line terminal 37 extending from the other end of coil 22, and a second line terminal 35 being connected with stationary contact 2. Line terminals 37 and 35 may extend through suitable insulating bushings (not shown) provided through openings in casing 15 or its cover 14, and container 15 is preferably filled up to level L with an arc extinguishing liquid, such as oil.

It will be apparent that when the current in the circuit exceeds a predetermined value, as on overloads, solenoid coil 22 will attract core 28 upwardly, and this upward movement of the core will be impeded by the dashpot action of the core in the cylindrical passage 10, it being necessary that the fluid trapped within passage 10 be forced to escape through the relatively small clearances between core 28 and coil insulation 26 and between the core and contact rod 6. Eventually, however, core 28 will be drawn up far enough to cause movement of the rod upwardly, in a manner to be described, and thus separate contact 4 from stationary contact 2 to open the circuit. As soon as the circuit has been interrupted, solenoid coil 22 will be deenergized and closing spring 16 will then be free to move the contact rod and its contact 4 back into engagement with stationary contact 2 to reclose the circuit. Such reclosing movement is also delayed by the dashpot action of core 28 in passage 10.

In order to limit the number of successive operations of the breaker on continuing overloads, there is provided a lockout tension spring 9 normally held stressed between a lug on cover 14 and lever 11 by a latch lever 17 under the control of counting mechanism 19. Lever 11 is pivoted at 21 on a lug depending from cover 14 and has its inner end pivoted to a sleeve 23 slidably mounted on the enlarged portion 38 of the contact rod. The outer end of lever 11 extends through a slot 25 provided in the side of casing 15, and has an operating eye 27 outside the casing for manual operation thereof. Counting mechanism 19 has an operating arm 29 adapted to be actuated by a flange 39 on the contact rod, and may be of any well-known type capable of counting a predetermined number of closely successive breaker operations to trip latch lever 17, such as that disclosed in the copending application of H. L. Rawlins et al., Serial No. 513,860, filed December 11, 1943, on Circuit Interrupters, and assigned to the same assignee of this invention. When lever 11 is released, lockout spring 9 then becomes operative to hold contact 4 at an open circuit position spaced from contact 2. Following an automatic lockout operation, the contacts may be manually reclosed by pushing the outer end of lever 11 upwardly, and this will restore the parts to the position shown in Fig. 1.

As previously pointed out, automatic reclosing circuit breakers are used in circuits for the protection of a number of fuses which may be of different ratings. Fig. 5 illustrates the time-current characteristic of one fuse FA and another fuse FB having a higher rating. There is also illustrated in Fig. 5, curve RB of an auto-

matic reclosing circuit breaker wherein time delay means, such as a dashpot is employed to obtain sufficient time delay to approximate the fuse characteristics on low currents. The difficulty in obtaining proper coordination of such circuit breakers and fuses is clearly shown in Fig. 5, where the breaker curve RB is shown to swing away to its lower end to the right of the normal location of the fuse curves. It is, therefore, extremely difficult to use a circuit breaker of this type to protect a fuse link, because although it is apparent from Fig. 5 that the two fuses can be readily coordinated in that fuse FA will blow and thus protect fuse FB at all currents, the circuit breaker RB will protect fuse FB only at low currents, and would afford no protection to this fuse at currents beyond the point where the curves intersect. It will be apparent that if the breaker could be provided with time delay means which would be less effective at higher currents than at lower currents, the recloser curve could be made to more nearly simulate a fuse curve, such as curve RA.

The automatic reclosing circuit breaker illustrated in Fig. 1 is constructed to have less time delay on higher overload currents, to thus more nearly approximate the time current characteristic of fuses. As shown in Fig. 2, the solenoid coil insulation comprises at least in part a dashpot sleeve 26 which is seated at its lower end in an annular recess provided in the lower supporting plate 24, and at its upper end engages an outer flange on a closure plug 34 to hold the plug in a similar annular recess in the upper supporting plate 24. Contact rod 36 has the enlarged upper portion 38 extending for a substantial distance within dashpot sleeve 26 when the breaker contacts are at their closed circuit position. A coil compression spring 40 is provided to react between the closed lower end of solenoid core 28 and the shoulder formed by enlarged portion 38 of contact rod 36. Between contact rod 36 and coil spring 40, there is positioned an actuating sleeve 42 for a purpose to be described.

It will be observed that the parts are shown in Fig. 2 as being at a position where solenoid core 28 has been drawn upwardly a substantial amount and is about to cause separation of the breaker contacts. As core 28 is drawn upwardly, it compresses spring 40 and normally when the spring pressure is high enough, it will force the breaker open. In order to insure opening of the contacts, actuating sleeve 42 is adapted to positively engage the shoulder formed by enlarged portion 38 of contact rod 36 to form a direct drive connection from the solenoid core to contact rod 36 at a point adjacent the upper end of core movement to positively separate the contacts.

However, as solenoid core 28 is drawn upwardly, it also acts as a dashpot piston working in dashpot sleeve 26, so that considerable pressure will be developed within sleeve 26 depending, of course, upon the force acting on core 28, and this depends upon the magnitude of the overload current energizing the solenoid coil 22. In any event, it will be noted that a differential piston is formed within dashpot sleeve 26 by the large area upper portion 38 of contact rod 36, and the small area lower portion of this rod. Accordingly, when an overload of relatively high current magnitude energizes solenoid coil 22, sufficient oil pressure is created within dashpot sleeve 26 as to form a hydraulic drive forcing contact rod 36 upwardly because of the differen-

tial piston action, and this will occur before actuating sleeve 42 engages the shoulder formed at enlarged portion 38 of the contact rod.

Exactly at what point in the path of travel of solenoid core 28 upwardly actual separation of the breaker contacts occurs will, of course, depend on the magnitude of overload current flowing in the circuit. In any event, separation of the breaker contacts will occur earlier on high overloads than it will for low overloads, resulting in a shift to the left of the lower end of the breaker curves as at RA (Fig. 5), to a position substantially paralleling the fuse curves FA and FB.

In Fig. 3 there is illustrated another arrangement for obtaining substantially the same resulting improvement in circuit breaker time-current opening characteristic, with many of the parts illustrated here being identical with those shown in Figs. 1 and 2, and accordingly, like reference numerals are employed to designate such like parts. In this embodiment of the invention a contact rod 6 of uniform size is provided having a second pin 36 for defining the upper limit of movement of core 28 on contact rod 6. A closure plug 44 is provided for the upper end of dashpot sleeve 26 and it has an annular recess 46 opening at the lower end of the plug and with side vent openings 48 adjacent the upper end of the plug. Closure plug 44 is not held stationarily between dashpot sleeve 26 and upper supporting plate 24 as in Fig. 2, but is free to move relative to the dashpot sleeve and contact rod 6, being normally held at the position shown in Fig. 3 wherein a flange at the upper end of the closure plug is held seated on the upper side of supporting plate 24, by a coil compression spring 50 engaging between plug 44 and spring retaining brackets 52 suitably secured on the upper supporting plate 24. Here, too, solenoid core 28 is shown at an upper position just prior to the point in its path of circuit opening movement where the breaker contacts are separated. It will further be apparent that vent openings 48 of closure plug 44 are normally closed since they are covered by dashpot sleeve 26 in the position shown in Fig. 3.

Closure plug 44 may be forced upward against the action of spring 50 so that fluid trapped within the dashpot may escape through vent openings 48, and the amount of such venting will be dependent upon the upward force developed by solenoid coil 22 and this, of course, is dependent on the magnitude of the overload current flowing in the circuit. On operation at relatively low overloads, the fluid pressure in dashpot sleeve 26 will not normally be sufficient to cause any upward movement of plug 44 and the circuit breaker will operate in its normal fashion, which (Fig. 5) comprises the common portion of time-current curves RA, RB. However, as the overload current increases, the force available for moving solenoid core 28 upwardly also increases, thereby developing greater pressures within dashpot sleeve 26, and closure plug 44 will be forced upward to begin to allow some venting of the dashpot. The amount of venting, of course, will be dependent on the magnitude of the overload current, as previously pointed out. With such additional venting, the resistance of the dashpot to movement of core 28 decreases so that a faster opening of the breaker contacts results to thereby shift the lower portion of the characteristic breaker curves to the left, as at RA, to a position more nearly approximating that of the characteristic curves of fuses.

Another advantage of the structure shown in

Fig. 3 is derived from the fact that when the solenoid core 28 is drawn upwardly, the force exerted by solenoid coil 22 varies inversely with the distance separating core 28 and plug 44. Thus, at lower values of overload current, the force required to start to move closure plug 44 upwardly to uncover vent openings 48 will not be reached until core 28 is substantially at the end of its circuit opening stroke. On high currents this force will be reached at an earlier point in the upward travel of core 28, and at very high current overloads this force may be realized substantially instantaneously so that vents 48 will be uncovered immediately.

Moreover, the length of core 28 and of closure plug 44 may be adjusted so that core 28 will engage the lower end of plug 44 substantially at the same time the lower end of core 28 engages pin 30 on contact rod 6 so that the upper end of dashpot sleeve 26 will always be vented when the breaker contacts are actually separated to thereby insure rapid separating movement of the breaker contacts.

The construction illustrated in Fig. 4 of the drawing is likewise similar in that there is employed many of the same parts previously illustrated, and these parts will, therefore, be designated by the same reference numerals. The solenoid core 54 illustrated in this embodiment of the invention is provided with vent openings 56 at opposite sides thereof adjacent the lower end of the core. Vent openings 56 are normally adapted to be closed by a sleeve valve 58 mounted within core 54 and normally held at an upper position against stop screws 60 by a coil compression spring 62 reacting between an interior flange at the upper end of valve sleeve 58 and the lower end of core 54.

This device operates in a manner similar to the device previously described except that valve sleeve 58 is operated to move relative to solenoid core 54 in response to a predetermined high rate of acceleration of solenoid core 54, rather than by the internal pressure developed within dashpot sleeve 32 as was the case in connection with the embodiment of the invention shown in Fig. 3 of the drawing. Normally, valve sleeve 58 will not be displaced, but where solenoid core 54 is accelerated upwardly by coil 22 at a fairly high rate as by relatively high overload currents passing through the circuit, then the inertia of valve sleeve 58 will cause it to lag sufficiently behind core 54 as to more or less uncover vent openings 56, thereby decreasing the resistance of the dashpot to movement on such high overload currents. The accelerating force which may be developed in solenoid core 54 is roughly proportional to the current flowing in the circuit, and insofar as the effect on the recloser is concerned, this will be substantially the same as that due to the construction shown in Figs. 2 and 3. This, therefore, results in changing recloser curve RB by shifting the lower end to the left, as at RA (Fig. 5).

It will be observed that an additional function is provided due to the structure shown in Fig. 4, in that pin 30 is positioned to engage valve sleeve 58 in core 54, when the latter has been moved upwardly a predetermined distance to uncover vent openings 56 just before contact separation occurs. This obviously allows free venting of the dashpot arrangement substantially at the end of the circuit opening movement of solenoid core 54 so that the final movement thereof which is em-

ployed to actually separate the breaker contacts will take place relatively rapidly.

There have been disclosed herein several modifications of applicant's invention comprising means for controlling the opening time of automatic reclosing circuit breakers having time delay means, by using the energy stored within the time delay device when the same is actuated to open the circuit so as to be effective to decrease the circuit opening times at least on high values of overload current. In one embodiment of the invention this is accomplished by a means which is responsive to the rate of acceleration of a part which is accelerated in accordance with the value of overload current in the circuit. In all cases there is accomplished a faster opening of the breaker contacts on higher current overloads, and at least in some cases a fast separation of the contact is also provided to thereby enhance the arc-extinguishing action of the circuit breaker.

Having described preferred embodiments of the invention in accordance with the patent statutes, it is desired that this invention be not limited to these particular structures, inasmuch as it will be apparent, particularly to persons skilled in the art, that many modifications and changes may be made in these particular devices without departing from the broad spirit and scope of this invention.

I claim as my invention:

1. An automatic reclosing circuit breaker, comprising, separable contacts, means having a part movable in response to overloads a predetermined distance before causing separation of said contacts, means for automatically reclosing said contacts in response to a circuit interrupting operation, means for delaying movement of said part on at least one circuit interrupting operation, and inertia means yieldably mounted on said part for limited relative movement, so as to be responsive to predetermined acceleration of said part, due to the occurrence of an overload above a predetermined value, for decreasing the resistance of said delay means.

2. An automatic reclosing circuit breaker, comprising, separable contacts, means having a part movable in response to overloads a predetermined distance before causing separation of said contacts, means for automatically reclosing said contacts in response to a circuit interrupting operation, means for delaying movement of said part on at least one circuit interrupting operation, normally inactive means for decreasing the resistance of said delay means, means responsive to a predetermined force exerted by said overload-responsive means by an overload above a predetermined value for actuating said resistance-decreasing means and means responsive to circuit opening movement of said part to a point adjacent the end of its predetermined movement for also actuating said resistance decreasing means.

3. An automatic reclosing circuit breaker, comprising, separable contacts, means having a part movable in response to overloads a predetermined distance before causing separation of said contacts, means for automatically reclosing said contacts in response to a circuit interrupting operation, dashpot means for delaying movement of said part on at least one circuit

interrupting operation, said dashpot means having a vent, valve means normally closing said vent but being responsive to pressure developed in said dashpot means by overloads above a predetermined value to uncover said vent, and means responsive to circuit opening movement of said part to a point adjacent the end of its predetermined movement for operating said valve means to uncover said vent.

4. An automatic reclosing circuit breaker, comprising, separable contacts, means having a part movable in response to overloads a predetermined distance before causing separation of said contacts, means for automatically reclosing said contacts in response to a circuit interrupting operation, dashpot means for delaying movement of said part on at least one circuit interrupting operation, the movable part of said dashpot means having a vent, valve means yieldably supported on the movable part of said dashpot at a normal position where it is movable with said movable part of the dashpot means and closes said vent, and said valve means being movable relative to said movable part in response to an acceleration of said movable part of the dashpot means at a rate greater than a predetermined amount, to open said vent.

5. An automatic reclosing circuit breaker, comprising, separable contacts, means having a part movable in response to overloads a predetermined distance before causing separation of said contacts, means for automatically reclosing said contacts in response to a circuit interrupting operation, dashpot means for delaying movement of said part on at least one circuit interrupting operation, the movable part of said dashpot means having a vent, valve means normally movable with said movable part of the dashpot means and closing said vent, said valve means being movable relative to said movable part in response to an acceleration of said movable part of the dashpot means at a rate greater than a predetermined amount to open said vent, and means responsive to circuit opening movement of said part of the overload-responsive means to a point adjacent the end of its predetermined movement for also moving said valve means to open said vent.
